ASH TRAY

Tsugio Kubota, Mill Valley, Calif., assignor to Schlage
Lock Company, a corporation

Application November 26, 1956, Serial No. 43,932

Term of patent 14 years

(Cl. D85—2)

FIG. 1

FIG. 2

FIG. 3

FIG. 4

Fig. 1 is a top plan view of an ash tray showing my new design;

Fig. 2 is a side elevation thereof;

Fig. 3 is a longitudinal cross section of the ash tray as taken along lines 3—3 of Figure 1; and

Fig. 4 is a left hand end view of Fig. 1.

I claim:

The ornamental design for an ash tray, as shown.
